(57) **CLAIM**

The ornamental design for a candy container, as shown and described.

DESCRIPTION

FIG. 1 is a top view of the candy container showing my new design;

FIG. 2 is a left side view thereof;

FIG. 3 is a front view thereof;

FIG. 4 is a right side view thereof;

FIG. 5 is a bottom view thereof;

FIG. 6 is a rear view thereof;

FIG. 7 is a perspective view thereof;

FIG. 8 is a perspective view thereof, shown with the cap open in condition of use;

FIG. 9 is a perspective view of FIG. 8 shown in an alternate position; and,

FIG. 10 is perspective view of FIG. 8 further shown in an alternate position.

The broken lines shown in the drawing disclosure are for illustrative purposes only and form no part of the claimed design.
